UNITED STATES PATENT OFFICE.

EDWARD FRIES, OF MOORES, PENNSYLVANIA.

PROCESS OF PREPARING MOLDS FOR CASTINGS.

1,345,162.

Specification of Letters Patent. Patented June 29, 1920.

Application filed October 15, 1919. Serial No. 330,692.

To all whom it may concern:

Be it known that I, EDWARD FRIES, a citizen of the United States, and a resident of Moores, county of Delaware, State of Pennsylvania, have invented certain Improvements in Processes of Preparing Molds for Castings, of which the following is a specification.

My invention relates to certain improvements in the process of preparing molds for making castings, particularly intricate castings of large size.

One object of my invention is to improve the process of preparing molds for making castings by dispensing with the ordinary portable drag section of a flask, in which the mold was formed and in which the casting was made.

A further object is to provide a bottom plate which will support the mold during the entire process.

A still further object is to so carry out the process that the mold can be baked without an inclosing flask, and to provide a fixed flask to receive the bottom plate, mold and cores and in which the casting is made.

These objects I attain in the following manner, reference being had to the accompanying drawings, in which:—

Fig. 1, is a view showing the mold in the box in which it was formed;

Fig. 2, is a perspective view of the pattern;

Fig. 3, is a perspective view of the mold on a bottom plate, ready to be placed in an oven to be heated to the required degree;

Fig. 4, is a view of the mold showing the cores assembled;

Fig. 5, is a view showing the mold and cores located in a permanent flask; and

Fig. 6, is a perspective view of the flask within a pit and the cope secured to the flask ready for pouring.

Heretofore, in making large molds such as those for cylinder castings for locomotives, the ordinary movable cope and drag sections of a flask were used, and the flask carried the mold from start to finish, and when the mold was baked it was baked with the drag section of the flask and when the cores were assembled a man had to stand in the flask and set the cores, and it was a difficult matter to see that all the intricate passages were clear of dirt or other foreign

matter, and that the cores were set in the proper positions. After this the drag, with its mold, was carried to the pouring floor and the cope located on it and the metal poured, then the flask was raised from the casting and sand and removed to a storage place for future use, the casting being carried from the floor.

The portable drag sections of the flask were large and heavy, necessitating the use of cranes, and they occupied considerable space. Furthermore, by the constant heating and cooling the flasks would crack, which would render them useless, and if the crack occurred during the pouring operation the molten metal would flow over the floor and serious accidents would result.

The above method required a very deep pattern, as a mold of the full height had to be made at the beginning of the process.

In ordinary foundry practice, the bottom plate of the flask is always larger than the flask so that the flask, as well as the mold, rests on the bottom plate. The flask must be removed from the bottom plate to allow for the removal of the mold and the sand adhering to it. By my improved process, the bottom plate carries the mold and is of such a size as to fit within the flask and, consequently, the flask can be located in a stationary position, preferably in a pit, while the bottom plate and the mold are inserted in the flask and, when the metal is poured therein, the casting is removed by withdrawing the bottom plate.

In carrying out my improved process and referring to Fig. 1, 1 is a box having end and side walls 2 and 3, respectively, and the box is rectangular, in the present instance. Pivotally mounted in this box are plates 4, the hinges 5 of which are pivoted to the ends 2 of the box, as clearly shown in the drawings. Between the opposite ends of these pivoted plates 4 and the side walls of the box are wedges 6, the end walls having shoulders 7 formed thereon against which the plates are held by the wedges.

When it is desired to make a smaller mold than that for which the box is intended, one or more plates 8 may be inserted in the box. 9 is a bottom plate and 10 is a pattern located on the plate 9 within the box. The mold 11 is formed on this pattern and a plate 12, which becomes the bottom plate of

the mold, is placed on the mold and the box. Both the box and the mold are of such a size as to receive the plate.

The box 1 is then raised from the bottom plate 9 and inverted, the plate 12 becoming the bottom plate. The wedges 6 are then removed, leaving the pivoted side plates 4 free to swing so that the box can be readily withdrawn from the mold. After this, the pattern is also withdrawn from the mold. In some instances, the pattern may be withdrawn first and then the box, leaving the mold on the bottom plate 12, as clearly shown in Fig. 3. Slings 13 are then attached to the bottom plate, as shown, and the slings are engaged by a cross beam of a crane, as illustrated in the drawings. The bottom plate 12, with the mold 11 thereon, is then conveyed to a position in front of an oven where it is transferred to a carriage adapted to a track leading into the oven. The carriage is then pushed into the oven and the mold is allowed to remain therein until the parts are properly baked, so that the sand will hold its position during the process of casting.

When the mold is removed from the oven certain cores 14 are placed in the mold, depending upon the character of the article being cast. It is then carried to the casting floor and the bottom plate 12, with the mold and cores thereon, is lowered into the permanent flask 15, which is made as shown clearly in Fig. 5, having fixed end walls 16, and an adjustable side wall 17, held by pins 18 adapted to holes in the end walls, as illustrated in Figs. 5 and 6, and a fixed side wall 17.

The remaining parts of the mold are then assembled to build the mold up to the proper level; these parts having been previously baked, and as the parts of the mold are assembled in the flask, sand is rammed between the walls of the flask and the mold, after which the cope 19 is placed in position on the fixed flask 15 and clamped thereto. That portion of the mold in the cope is formed in the present instance in the ordinary manner. The pouring head 20 is placed in position and the metal poured. At the proper time the cope is removed and the slings 13 are engaged by the hooks of a crane and the bottom plate 12, with the casting thereon, is removed from the fixed flask 15 which can be made ready for another mold.

By this process, I avoid the necessity of lifting the heavy flasks each time a casting is made, and I also avoid the necessity of baking the mold in a flask, as the flask is permanently located in a pit. It can be made much heavier than the ordinary flask and will last indefinitely.

By locating the flask within the pit, in

the event of the flask cracking, or a break 65 occurring in any part thereof, the molten metal will flow into the pit and not over the floor, thus avoiding accidents and injuries to the men employed.

By my improved method, I am enabled 70 to make a single flask which can be adjusted to fit molds of different dimensions. Heretofore, particularly in casting cylinders of locomotives, each special size of cylinder had to have a flask of a corresponding size. 75 This necessitated carrying a large number of flasks in storage, or providing special flasks when cylinders of special sizes were to be cast. Furthermore, by making the mold as described and assembling it as 80 shown, all of the passages between the parts of the mold and the cores can be examined and can be readily freed from dirt, as there is no inclosing flask for the mold during the baking operation, or when the parts of the 85 mold are assembled. The assembled mold is placed in the fixed flask as the last operation.

I claim:

1. The process herein described of making molds for castings, said process consisting in first placing a pattern within a forming box, making a mold within the box, placing a bottom plate on the mold, inverting the box, removing the box and pattern from the mold, baking the mold while on the bottom plate without a flask, then carrying the mold by the bottom plate to a fixed flask having an inner dimension of a size to receive the bottom plate, lowering 100 the bottom plate, with the mold, into the flask, and closing the flask for pouring.

2. The process herein described of making a mold for casting, said process consisting in placing a pattern within the forming 105 box, making a mold within the box, placing a bottom plate on the mold, inverting the box, when removing the box and pattern from the mold, baking the mold while on the bottom plate without a flask, placing the 110 bottom plate, with the mold thereon, in a fixed flask, lowering the plate and the mold within the flask, closing the flask, pouring the metal in the flask, and finally removing the casting produced by lifting the bottom 115 plate out of the flask.

3. The process herein described of making molds for castings, said process consisting in first placing a pattern within a box and making a sand mold within the box and around the pattern, mounting a bottom plate on the mold, inverting the box, with the mold and pattern therein, removing the box and pattern from the mold, then baking the mold while on the bottom plate and without a flask, locating the bottom plate and mold within a fixed flask, building up the mold to the level of the top of the fixed flask,

mounting a cope thereon with another portion of the mold therein, and finally pouring the molten metal into the mold.

4. The process herein described of preparing molds, said process consisting in first placing a pattern within a box, forming a mold within the box and on the pattern, placing a bottom plate on the completed mold, inverting the box, with the mold and

pattern therein, removing the box and pattern from the mold and bottom plate, baking the mold, then assembling cores on the mold while on the bottom plate without a flask, then placing the mold with the cores thereon in a fixed flask, and placing the cope, with the other section of the mold therein, in position on the fixed flask ready for pouring.

EDWARD FRIES.
